UNITED STATES PATENT OFFICE.

WILLIAM A. FIFER, OF QUINCY, ILLINOIS, ASSIGNOR TO THE QUINCY SHOW CASE WORKS, OF QUINCY, ILLINOIS, A CORPORATION OF ILLINOIS.

SHOW-CASE.

1,369,091.

Specification of Letters Patent. Patented Feb. 22, 1921.

Application filed June 7, 1920. Serial No. 387,268.

To all whom it may concern:

Be it known that I, WILLIAM A. FIFER, a citizen of the United States, residing at Quincy, in the county of Adams and State 5 of Illinois, have invented certain new and useful Improvements in Show-Cases; and I hereby declare that the following is a full, clear, and exact description thereof, reference being had to the accompanying drawings, which form part of this specification.

This invention is a novel show case and especially intended for displaying articles that are required to be kept cool and dry; and its object is to provide a case wherein 15 articles will be advantageously displayed, the front, ends, and top of the case being made of glass; so that the goods placed in the case can be displayed in the most advantageous and attractive manner, and the case present an ornamental and attractive appearance; and which has an interior ice 20 compartment whose walls are also made of glass, so that the ice compartment enhances the attractive appearance of the case instead of detracting therefrom.

I will explain the invention with reference to the accompanying drawings and set forth in the claims the essentials of the invention and novel features of construction and novel 30 combination of parts for which protection is desired.

In said drawings:

Figure 1 is a perspective view of a show case embodying the invention.

Fig. 2 is in part a rear elevation and in part a longitudinal vertical section of such case.

Fig. 3 is in part a top plan view and in part a horizontal section of the case.

Fig. 4 is a vertical transverse section of the case on the line 4—4, Fig. 2, showing the ice rack partly withdrawn in dotted lines.

Fig. 5 is an enlarged perspective view of 45 part of the case showing the ice rack partially pulled out.

The case comprises a bottom portion which may be of any suitable construction, but preferably is composed of a wooden 50 frame comprising front member 1, rear members 1^b, end members 1^b, and intermediate transverse members 1^c, covered by a suitable flooring 1^d; and attached to front member 1 and to the end members 1^b are 55 facing slabs 1^e and 1^f. Preferably the floor

1^e and facings 1^e and 1^f are made of marble, or the like, to impart an ornamental appearance and durable finish to the case.

At the rear side of the case and rigidly connected with the rear side of the base frame are corner uprights 2, between which are intermediate uprights 2^a; which are all connected to a top bar 2^c. The adjacent uprights 2 and 2^a are connected adjacent the floor of the case by a bar 2^d (Fig. 2), and the intermediate uprights 2^a are connected below the top bar 2^c by a bar 2^e, and also by a bar 2^f below the bars 2^d.

Between each upright 2 and the adjacent upright 2^a is a door 3, which may be of any suitable construction, but preferably has its top and sides rabbeted to engage corresponding opposite rabbeted surfaces on the door frame (formed by the uprights 2, 2^a and bars 2^c, 2^d) so as to make a close practically air tight fit between the door and the frame when the door is closed. The doors may be hinged to uprights 2 by hinges 3^a of any suitable kind, and may be tightly secured when closed by fasteners 3^b of any suitable kind.

Intermediate the uprights 2^a is a door 4 similar to doors 3 (framed by the uprights 2^a and bars 2^e, 2^f). The door 4 may be hinged to one of the uprights 2^a by hinges 4^a, and may be fastened by any suitable means when closed, like the doors 3; such fastening devices being well known. It is not necessary to show them in detail.

Above the door 4 is a smaller door 5 (framed by the uprights 2^a and bars 2^e, 2^f) to permit access to the case above the door 4. The doors 3 and 5 permit access into the interior of the case, while the door 4 permits access to the ice chamber, hereinafter described.

The end walls 10, front 10^a and top 10^b of the case are all formed of plate glass, fitted together as shown and connected by any suitable means; the end and front walls 10 being supported upon the base; and the top upon the end, front and back walls of the case.

If desired the front wall 10^a could be rearwardly inclined and the end and back walls 10^b and top-plate of the cases correspondingly altered to suit.

Within the case is an ice chamber, of which door 4 forms the back; the sides 6, front 6^a, and top 6^b of this ice chamber are 110

formed of glass plates which are fitted together and secured by any suitable means. The sides 6 may have cut away portions 6^a, 6^b at top and bottom to permit free circulation of air from the ice chamber into the case and return.

The bottom of the ice chamber is preferably formed below the floor 1^c of the show case, and may be lined with metal 7, so that 10 it cannot leak, and be provided with a drain pipe and drip cup 7^a, of usual construction. Access may be had to the usual drip water pan (not shown) placed beneath the drip cup 7^a when the case is in use through a 15 drop door 7^b, hinged to bar 2^w below the door 4, as shown:

Within the ice compartment is a slide- 20 able ice rack 8, which is provided with side bars 8^a that rest upon guides 9 within, and on opposite sides of the lower part of the ice chamber. Arranged above the guides 9 at the sides of the ice compartment are guide strips 9^a, which have cut-away portions 9^b at their inner ends for the accommodation of pins 8^c, attached to the side bars 8^a of the ice rack; which pins can enter the cut-away portions 9^b of strips 9^a and permit the rack 8 to be drawn outward to the position indicated in Fig. 5, and in dotted lines 25 in Fig. 4, so that ice can be readily placed on the rack 8, and then the latter slid back into the ice compartment and the door 4 closed.

If it is desired to entirely remove the ice 30 rack for cleaning it should be pushed in as far as it will go, so that pins 8^c will clear the inner end of the guide strips 9 (Fig. 3) and the rack can then be lifted vertically clear of the guide strips and removed from 35 the chamber.

Within the case at opposite sides of the ice compartment are arranged a series of shelves 11, which are preferably made of plate glass and supported on brackets 11^a 40 attached to the uprights 2, 2^w. The top plate 6^c of the ice compartment also serves as a shelf, and if the case is extended additional shelving may be placed in the case above the top of the ice compartment, if 45 desired.

Such case permits advantageous display.

of all the goods placed therein. The ice compartment having transparent walls, does not present an unsightly appearance, and when clean ice is placed therein the appearance of the case is enhanced thereby. The case is particularly well adapted for keeping perishable articles cool, dry, and free from dust and dirt. All parts are readily accessible, and the floor, and shelving, and ice rack are supported and constructed in a substantial and durable manner. The practical advantages of such a case, its utility, and desirability will be readily appreciated by those familiar with the art.

What I claim is:

1. A display case having a base formed of side, front, rear, and intermediate pieces and a flooring; end and intermediate uprights connected to the rear side of the base and rising therefrom; a top bar connecting said uprights, intermediate bars connecting the end and intermediate uprights at about the floor level, a bar connecting the adjacent intermediate uprights; doors closing the spaces between the end and intermediate uprights, and doors closing the spaces between the intermediate uprights; glass plates mounted on the front and ends of the base and forming the front and end walls of the casing, and a glass plate mounted on the front and end walls and forming the top of the case.

2. A display case having a base formed of side, front, rear, and intermediate pieces and a flooring; end and intermediate uprights connected to the rear side of the base and rising therefrom, a top bar connecting said uprights, intermediate bars connecting the end and intermediate uprights; a bar connecting the intermediate uprights below the top bar, and a bar connecting the intermediate uprights about the flooring level; doors closing the spaces between the end and intermediate uprights, doors closing the spaces between the intermediate uprights; and front, end and top walls mounted on the base.

In testimony that I claim the foregoing as my own, I affix my signature.

WILLIAM A. FIFER.
